UNITED STATES PATENT OFFICE

E HARRISON SCOTT, OF RICHMOND, INDIANA, ASSIGNOR TO JOHNSON AUTOMOBILE SHEET METAL WORKS, OF RICHMOND, INDIANA, A CORPORATION OF INDIANA.

EXPANSION-ROLL FOR SHEET-METAL-FORMING MACHINES.

1,360,450.

Specification of Letters Patent. Patented Nov. 30, 1920.

Application filed October 16, 1919. Serial No. 331,099.

To all whom it may concern:

Be it known that I, E HARRISON SCOTT, a citizen of the United States, residing in the city of Richmond, in the county of Wayne, 5 State of Indiana, have invented certain new and useful Improvements in Expansion-Rolls for Sheet-Metal-Forming Machines, of which the following is a full, clear, and comprehensive specification and exposition, 10 the same being such as will enable others to make and use the same with exactitude.

The object of my present invention, broadly stated, is to provide an expansive and self-compensating roll, especially intended to be employed as a part of sheet metal forming machines, the same being strong and durable in construction, simple in character, compensating and effective in action, adapted to give the highest degree 20 of efficiency in practice, and which can be manufactured, sold, and installed at a comparatively low price.

My invention is especially intended to be incorporated with machines for forming automobile fenders, wherein sheets of metal 25 are given longitudinal compound curves and cross sectional curves, as well as forming marginal flanges thereon, to do which a male and a female roll is employed, with 30 sheets of metal adapted to pass therebetween. For accomplishing the purposes just stated the female roll is formed concave and the male roll is formed convex, the longitudinal curvature of each being substantially identical with each other, whereby 35 they will nest together, and the female roll being provided with end flanges or abutments between which the ends of the male roll extends.

40 Means have heretofore been employed to retain the faces of the two rolls normally in resilient contact with each other, but no means have heretofore been employed to retain the ends of male roll normally in contact, or nearly so, with the flanges of the 45 female roll. While the rolls are new this is not required, providing the length of the male roll is accurately gaged to the distance between the flanges of the female roll, so that the sheet metal will pass tightly therebetween. But the ends of the male roll and the inner faces of the flanges of the female roll soon become worn or the gage of the material may be changed, and then the mate-

and uneven. Therefore to compensate for said wear and changes in the gage is the primal object of this invention, which manifestly will insure a uniform and perfect product and at the same time contributing 60 to considerable saving in time and expense.

Other minor and subsidiary objects will suggest themselves to one familiar with the art, in the course of the following specification, and that which is new will be correlated in the claims.

The means I employ for carrying out the objects of my invention in a practical and a mechanical manner are shown in the accompanying drawings, in which—Figure 1 is a 70 central longitudinal section of the parts embodying the preferred construction of my invention. Fig. 2 is an inside elevation of one member of the male or upper roll. Fig. 3 is an outside end elevation of a modified 75 form for construction of the male roll. And Fig. 4 is an outside front elevation of the modified form for the invention.

Similar indices denote like parts throughout the several views.

In order that the construction, the operation, and the advantages of my invention may be more fully understood and appreciated I will now take up a detailed description thereof, in which I will set forth the 85 several parts as fully and as comprehensively as I may.

Referring now to the drawings in detail, numerals 1 and 2 denote the two spaced apart shafts, which are so incorporated into 90 a sheet metal forming machine that they revolve in directions opposite to each other, and are retained in spaced relationship with relation to each other.

As is shown in Figs. 1 and 2 my preferred construction includes a male roll, which includes two members 3 and 4, which are identical with each other, each being cup-shaped and having the respective closed ends 5 and 6 which are at right-angles to the shaft 1. The inner ends of said members are open, with their edges adapted to contact with each other. Said members are mounted concentrically on the shaft 1, as hereinafter set forth. Extending inward 100 around the shaft 1 from the respective ends 5 and 6 are the flanges 7 and 8. Each of the members 3 and 4 is adapted to have a sliding movement on and longitudinally 105 of the shaft 1, as hereinafter set forth.

10, respectively. By the above it will be noticed that I provide a convex and hollow cone or roll, mounted slidably on the shaft 1, but at all times carried revolubly therewith. Located in the hollow of the upper roll is a comparatively large expansion spring 12, which is spaced from but concentric with the shaft 1, with its end portions fitting around the flanges 7 and 8 and seated 10 against the inner faces of the ends 5 and 6, whereby the members 3 and 4 are normally forced resiliently apart by the expansive force of the spring 12.

Rigidly mounted on the shaft 2 is the female or concave roll 11 which has end flanges 13 and 14 formed integral therewith. The space between the flanges 13 and 14 is only slightly more than is the length of the upper roll when the members 3 and 4 thereof are contacted with each other. Surrounding the shaft 2 and contacted with the ends of the roll 11 are the collars 15 and 16, and they extend outward to the bearings of the shaft 2 to retain the lower roll in proper position longitudinally.

In assembling the roll shown in Fig. 1 the members 3 and 4 are first clamped together, against the expansive force of the spring 12, and while in this condition it is inserted between the flanges 13 and 14, and then when the clamp is removed and the parts are otherwise arranged in operative condition the ends 5 and 6 will press resiliently against the flanges 13 and 14.

The sheet metal to be formed is run between the rolls, thereby pressing the material into concavo-convex shape, with marginal flanges formed at right-angles to the shafts 1 and 2, the latter being pressed 40 between the ends 5 and 6 and the flanges 13 and 14. By the above it is apparent that all wear of the ends 5 and 6 and of the flanges 13 and 14 and changes in the gage of the material will be taken up by the 45 spring 12, whereby the pressure on the material will always be uniform and of the proper degree.

In Fig. 4 it is shown that I provide a solid upper roll portion A, of the same shape as the roll shown in Fig. 1, except that the main central portion is slightly shorter, with end plates 17 and 18 secured to each end of the body A, by means of the respective sets of screws 19 and 20. The thickness of 55 said plates is such as to form the roll A of the proper length to fit between the flanges 13 and 14 as shown. Then as the faces of the plates 17 and 18 and the flanges 13 and 14 wear then the screws 19 and 20, or both, 60 may be loosened and one or more shims, such as sheets of paper or metal, may be inserted between the plates 17 and 18 and the ends of the roll A, after which the said screws should be tightened; this of course

will compensate for the wear or when the thickness of the material is changed and permit the rolls to function as before.

I desire that it be understood that various changes may be made in the several details of construction without departing from the spirit of my invention and without sacrificing any of the advantages thereof which are new and useful.

Having now fully shown and described my invention, what I claim and desire to secure by Letters Patent of the United States, is—

1. An expansion roll comprising a pair of cup-shaped members both mounted on a shaft concentrically thereof with the edges of said members adapted to contact with each other, a spring surrounding the shaft and located within said members and adapted to normally force said members resiliently apart, all substantially as shown and described and for the purposes set forth.

2. An expansion roll for sheet metal forming machines, in combination with a shaft, a pair of cup-shaped roll members formed identical with each other, both members being mounted concentric of and slidable on said shaft and adapted to be carried revolubly therewith with the edges of said members adapted to contact with each other forming a hollow interior in the roll formed by said members, an inwardly extending collar integral with each member of the roll and each surrounding said shaft, and an expansion helical spring located in the hollow of the roll with its end portions fitting around the respective collars and adapted to normally force said members of the roll apart.

3. A construction of the nature set forth comprising in combination with a pair of revoluble shafts spaced apart, a roll rigidly mounted on and concentric with one of said shafts, end flanges carried by said roll and projecting out at right-angles thereto, an expansible roll comprising a pair of cup-shaped members both slidably mounted on the other one of said shafts and adapted to be carried revolubly therewith with the edges of said members approaching near to each other, a helical spring located in said members and adapted to force said members into resilient contact with the flanges of the first mentioned roll.

4. In combination with a pair of spaced apart shafts located parallel with each other, a concave roll rigidly mounted on one of said shafts, end flanges carried by said roll and extending out at right-angles thereto, a convex roll slidably mounted on the second shaft and adapted to be carried revolubly therewith with its surface in contact with the concave roll, said second roll being divided circumferentially into two por-

tions which are independent of each other, a helical spring located within the two portions of the second roll and adapted to normally force the ends of the second roll into contact with the flanges of the first mentioned roll.

5 In testimony whereof I have hereunto

subscribed my name to this specification in the presence of two subscribing witnesses.

E HARRISON SCOTT.
